Thomas J. Kent,
By J. P. Cooley,
Attorney.

UNITED STATES PATENT OFFICE.

THOMAS J. KENT, OF PITTSBURG, PENNSYLVANIA, ASSIGNOR OF ONE-HALF TO SAMUEL B. CHARTERS AND WILLIAM H. DAUGHENBAUGH, OF PITTSBURG, PENNSYLVANIA.

SWITCH-THROWING DEVICE.

SPECIFICATION forming part of Letters Patent No. 706,668, dated August 12, 1902.

Application filed March 4, 1902. Serial No. 98,632. (No model.)

To all whom it may concern:

Be it known that I, THOMAS J. KENT, a resident of Pittsburg, in the county of Allegheny and State of Pennsylvania, (whose post-office address is 36 Monongahela street, in said Pittsburg, county and State aforesaid,) have invented a new and useful Improvement in Switch-Throwing Devices; and I do hereby declare the following to be a full, clear, and

10 exact description thereof.

My invention relates to switch-throwing devices, and has special reference to such devices as are used in connection with railway, traction, and other cars.

15 The object of my invention is to provide a cheap, simple, and effective device for throwing switches from the car by the operator and during the movement of the same without compelling such operator to leave the car.

20 My invention consists, generally stated, in the novel arrangement, construction, and combination of parts, as hereinafter more specifically set forth and described, and particularly pointed out in the claims.

25 To enable others skilled in the art to which my invention appertains to construct and use my improved switch-throwing device, I will describe the same more fully, referring to the accompanying drawings, in which—

30 Figure 1 is a perspective view of the end of a car and tracks, showing my invention applied thereto. Fig. 2 is an enlarged plan view of such tracks. Fig. 3 is an edge view of the switch-bar. Figs. 4 and 5 are views 35 of the pivotal connections for such switch-bar. Fig. 6 is a perspective view of the casting-plate for the end of the switch-bar, and Fig. 7 is a perspective view of the guide for the operating-lever.

40 Like letters and symbols of reference herein indicate like parts in each of the figures of the drawings.

The main tracks are shown at 1 and are provided with the throw-out tracks 2, connected 45 thereto by the switch-point I, which is pivoted at one end i, while its opposite end has a connecting-rod E, pivoted to a bearing i' thereon and to one end c of a switch-bar C, and this switch-bar C is pivoted at or about 50 its center to a timber or plank B, laid between

the tracks 1, by means of a pin D, which passes through a bushing H in said bar C and plank B. The opposite end c' of the switch-bar C is diamond-shaped, so as to form the inclined faces b b' thereon, and such end c' rests within the casting-plate A, which is placed between the tracks 1 at the end of the plank B and provided with upwardly - extending inclined flanges a a' at each side thereof.

55 The end of a car is shown at 2', having the platform 2" thereon and which extends from the end of the car in the ordinary manner and forms a portion of the floor 3', while an opening or slot 3 is formed in said floor 3' on the platform 2", over and within which is 60 placed and secured the guide G, and this guide G is provided with the two pockets g g' thereon, formed by the inclined central portion g² therein. The operating-lever F is pivoted at f to the bottom of the floor 3' and 65 extends up through the guide G, said lever F being provided with a spiral spring 4, connected thereto and to the bottom of the floor 3', while its lower end is provided with the shoe F', having the inclined faces f' f² thereon. 70

75 The use and operation of my improved switch-throwing device are as follows: The switch-point I and the bar C being in the positions shown in Figs. 1 and 2, with the car approaching the same in the direction of the arrow, Fig. 1, and it is desired to continue the movement or travel of the car along the main tracks 1, all that is necessary is for the operator to grasp the upper end of the lever F on the end 2' of the car and throw said lever into the pocket g of the guide G, which will cause the shoe F' on the lower end of said lever F to be directed by the flange a to come in contact with the inclined face b on the end c' of the bar C when the end 2' of the car reaches the position over the end c', and after the end F' passes the face b' the operator can 90 release his hold upon the lever F, and the spring 4 will return the lever F to the position shown in Fig. 1, which will cause the end c' of said bar C to move to one side in the direction of the arrow, Fig. 2, and cause its opposite end c to move in the opposite direction by means of the pivot-pin D in said bar C, when by reason of the rod E being con- 95 100

nected to the free end of the point I and to the end c of the bar C it will act to throw out said point on its pivot end i from the main tracks 1, and so permit said car to travel along 5 said tracks 1. After the switch-point I has been thus opened and it is desired to close the same, so as to permit the car approaching such point to travel onto the side tracks 2, all that is required is for the operator on 10 the car to grasp and throw the lever F into the pocket g' of the guide G in the floor 3' on the other side of the central portion g² from the pocket g, which will cause the shoe F' on said lever F to be directed by the flange a' to 15 come in contact with the inclined face b' on the end c' of the bar C when the end 2' of said car reaches the position over the end c', and after the end F' passes the face b the operator can release his hold upon the lever F and the 20 spring 4 will return the lever F to place, as shown in Fig. 1. This will cause the end c' of the bar C to move toward the arrow shown 25 in Fig. 2 and cause its opposite end c, with its rod E connected thereto and to the free end of the switch-point I, to move in the opposite direction through the pivot-pin D and so act to move said point I to a position against the main tracks 1, which will enable the car to pass from the main tracks 1 onto 30 the side tracks 2. The spiral spring 4, connecting the lever F and platform 2", will keep said lever clear of the track and switch-throwing parts when not in use, and the inclined flanges a on the casting-plate A will assist in 35 directing the shoe F' on the lever F against the inclined faces b b' on the end c' of the switch-bar C.

Various modifications and changes in the construction, design, and arrangement of the 40 various parts of my improved switch-throwing device may be resorted to without departing from the spirit of the invention or sacrificing any of its advantages.

It will thus be seen that my improved 45 switch-throwing device is positive in its movements and can be conveniently operated at will by the operator from the car, and its use will permit the switches to be thrown to their positions without the operator being compelled 50 to stop or slacken up the movement of the car.

What I claim as my invention, and desire to secure by Letters Patent, is—

1. In railway-switch-operating mechanism, 55 a car-platform having a guide in the floor thereof provided with two pockets therein, a lever adapted to fit within and swing in said guide, in combination with a pivoted switch-bar located between the tracks, having one end connected to the switch-point, whereby by swinging the lever into one of said pockets the lower end thereof will engage the free end on the switch-bar and throw the switch-point to the position desired.

65 2. In railway-switch-operating mechanism, a car-platform having a guide in the floor thereof provided with pockets therein, a le-

ver adapted to fit within and swing in said guide, in combination with a pivoted switch-bar located between the tracks having one end connected to the switch-point and its opposite end provided with inclined faces thereon, whereby, by swinging the lever into one of the said pockets the lower end thereof will engage one of the inclined faces on the switch-bar and throw the switch-point to the position desired.

3. In railway-switch-operating mechanism, a car-platform having a guide in the floor thereof provided with two pockets therein, a lever pivoted to said floor and adapted to fit within and swing in said guide, in combination with a pivoted switch-bar located between the tracks and having one end connected to the switch-point, whereby by swinging the lever into one of the said pockets the lower end thereof will engage the free end on the switch-bar and throw the switch-point to the position desired.

4. In railway-switch-operating mechanism, 90 a car-platform having a guide in the floor thereof provided with two pockets therein, a lever pivoted to said floor and adapted to fit within and swing in said guide, in combination with a pivoted switch-bar located between the tracks having one end connected to the switch-point and its opposite end provided with inclined faces thereon, whereby by swinging the lever into one of the said pockets the lower end thereof will engage one of the inclined faces on the switch-bar and throw the switch-point to the position desired.

5. In railway-switch-operating mechanism, a car-platform having a guide in the floor thereof provided with two pockets therein, 105 a lever adapted to fit within and swing in said guide, in combination with a pivoted switch-bar located between the tracks and having one end connected to the switch-point, a plate having inclined flanges thereon around the free end of said switch-bar, whereby by swinging the lever into one of said pockets the lower end thereof will be directed by one of said flanges to engage the free end of said switch-bar and throw the switch-point to the 110 position desired.

6. In railway-switch-operating mechanism, a car-platform having a guide in the floor thereof provided with pockets therein, a lever adapted to fit within and swing in said guide, 120 in combination with a pivoted switch-bar located between the tracks having one end connected to the switch-point and its opposite end provided with inclined faces thereon, a plate having inclined flanges thereon around the inclined face end of said switch-bar, whereby by swinging the lever into one of said pockets the lower end thereof will be directed by one of said flanges to engage one of the inclined faces on said switch-bar and 125 throw the switch-point to the position desired.

7. In railway-switch-operating mechanism, a car-platform having a guide in the floor thereof provided with pockets therein, a lever

pivoted to said floor and adapted to fit within and swing in said guide, in combination with a pivoted switch - bar located between the tracks and having one end connected to the switch-point, a plate having inclined flanges thereon around the free end of said switch-bar, whereby by swinging the lever into one of said pockets the lower end thereof will be directed to engage the free end of said switch-bar and throw the point to the position desired.

8. In railway-switch-operating mechanism, a car-platform having a guide in the floor thereof provided with pockets therein, a lever pivoted to said floor and adapted to fit within and swing in said guide, in combination with a pivoted switch-bar located between the tracks and having one end connected to the switch-point and its opposite end provided with inclined faces thereon, a plate having inclined flanges thereon around the inclined face end of said switch-bar, whereby by swinging the lever into one of said pockets the lower end thereof will be directed by one of said flanges to engage one of the inclined faces on said switch-bar and throw the switch-point to the position desired.

9. In railway-switch-operating mechanism, a car-platform having a guide in the floor thereof provided with pockets therein, a lever pivoted to said floor and adapted to fit within and swing in said guide, a spring connected to said lever and platform to hold the lever above the tracks, in combination with a pivoted switch-bar located between the tracks and having one end connected to the switch-point, whereby by swinging the lever into one of said pockets the lower end thereof will engage the free end of the switch-bar and throw the switch-point to the position desired.

10. In railway-switch-operating mechanism, a car-platform having a guide in the floor thereof provided with pockets therein, a lever pivoted to said floor and adapted to fit within and swing in said guide, a spring connected to said lever and platform to hold the lever above the tracks, in combination with a pivoted switch-bar located between the tracks and having one end connected to the switch-point, whereby by swinging the lever into one of said pockets the lower end thereof will be directed by one of said flanges to engage one of the inclined faces on said switch-bar and throw the switch-point to the position desired.

with a pivoted switch-bar located between the tracks having one end connected to the switch-point and its opposite end provided with inclined faces thereon, whereby by swinging the lever into one of said pockets the lower end thereof will engage one of the inclined faces on the switch-bar and throw the switch-point to the position desired.

11. In railway-switch-operating mechanism, a car-platform having a guide in the floor thereof provided with pockets therein, a lever pivoted to said floor and adapted to fit within and swing in said guide, a spring connected to said lever and platform to hold the lever above the tracks, in combination with a pivoted switch-bar located between the tracks and having one end connected to the switch-point, a plate having inclined flanges thereon around the free end of said switch-bar, whereby by swinging the lever into one of said pockets the lower end thereof will be directed to engage the free end of said switch-bar and throw the point to the position desired.

12. In railway-switch-operating mechanism, a car-platform having a guide in the floor thereof provided with pockets therein, a lever pivoted to said floor and adapted to fit within and swing in said guide, a spring connected to said lever and platform to hold the lever above the tracks, in combination with a pivoted switch-bar located between the tracks and having one end connected to the switch-point and its opposite end provided with inclined faces thereon, a plate having inclined flanges thereon around the inclined face end of said switch - bar, whereby by swinging the lever into one of said pockets the lower end thereof will be directed by one of said flanges to engage one of the inclined faces on said switch-bar and throw the switch-point to the position desired.

In testimony whereof I, the said THOMAS J. KENT, have hereunto set my hand.

THOMAS J. KENT.
